TELEPHONE-EXCHANGE SYSTEM.

1,116,541.

Specification of Letters Patent.

Patented Nov. 10, 1914.

Application filed August 10, 1912. Serial No. 714,422.

To all whom it may concern:

Be it known that I, MORTON L. JOHNSON, citizen of the United States, residing at Chicago, in the county of Cook and State of Illinois, have invented a certain new and useful Improvement in Telephone-Exchange Systems, of which the following is a full, clear, concise, and exact description, reference being had to the accompanying 10 drawings, forming a part of this specification.

My invention relates to communicating systems and, in one embodiment, relates to those telephone exchange systems having 15 equipment for effecting connection between a calling line and a desired line by the co-operation of operators located at different positions, though the invention is not to be restricted to its use in connection with 20 telephone exchange systems. There is a variety of such systems in which two operators thus coöperate and I do not therefore limit myself to any particular system in which two operators coöperate to establish 25 a single telephone circuit. The operators at these positions were able to converse by means of telephonic circuits extending between these positions whereby the receiving operators were informed of connections 30 to be established, a method of operation that was attended by difficulties and objections among which were the frequent necessity on the part of the calling subscribers to repeat the numbers of desired lines or 35 other information, delays imposed upon a calling subscriber while awaiting response on the part of the second operator, the delays to which the first or receiving operators were subjected because of the time required for the second operators to respond 40 and check up the message received from the first operators, and the unequal distribution of the traffic load imposed upon the second operators. I overcome these difficulties 45 by employing a speech recording and reproducing apparatus for reproducing recorded speech in the presence of the second operator and operable at the first operator's position, as I have practiced the invention, whereby the first operator conveys 50 the information in recorded form to the second operator's position where it is available to the second operator to suit her convenience and capacity.

55 In a connection which is being estab-

lished the speech recording and reproducing apparatus is coupled with the link that is being handled by the second or connecting operator so that when this operator hears the record that informs her of the number of the desired line she will employ the link coupled with the talking device and effect its connection with the desired line so that she need not be informed by the first or receiving operator either of the number of the calling line or the number of the link to be employed. The record is desirably impressed upon the talking device by telephonic current transmitted by way of the link connector but the invention is not to be limited to this method of coupling the link connector and the talking device. The receiving and connecting operators' positions may be in the same building or in 75 widely separated buildings yet their positions would in effect be at the same exchange and the claims are drawn in contemplation of this view.

I will explain my invention more fully 80 by reference to the accompanying drawings showing one embodiment thereof as employed in connection with telephone exchange systems and in which drawings—

Figures 1, 2 and 3, taken collectively and 85 in numerical order with the lines at the tops of the sheets in alinement, represent a telephone exchange system equipped in accordance with the invention.

Two stations 120 and 190 are illustrated, 90 the first being considered the calling station and the second a called station, by way of example. Each telephone station includes a switch hook 1, a telephone receiver 2, a telephone transmitter 3, a call bell 4, 95 and a condenser 5, the switch hook when supporting the telephone receiver establishing a bridge for the call bell and condenser and when free of the receiver establishing a metallic continuous bridge including the telephone receiver and transmitter. These telephone stations are illustrated as 100 extending to one type of telephone exchange in which an idle operator is selected by means of selecting mechanism that is not included in an established circuit between calling and called stations and which equipment is covered by the application of Elmer R. Corwin, Serial No. 503,345, filed 105 June 21, 1909. The invention, however, is 110

not to be limited to any particular telephone exchange equipment, the telephone exchange equipment illustrated being selected merely for the sake of example. In the 5 embodiment of the invention illustrated both telephone lines leading to stations 120 and 190 are adapted for selective association with the telephone equipment at various operators' positions and in the system 10 shown the operator who becomes telephonically connected with a calling line informs a second or B operator of the connection desired by means of speech recording and reproducing apparatus that is operable in the presence of the B operator to 15 reproduce the recorded speech and is operable by the A operator to record the speech of the A operator.

Assuming that the party at station 120 20 desires communication with the party at station 190, the party at station 120 will remove the telephone receiver from its switch hook thereby establishing a circuit traceable from the grounded common battery 6, the lower winding of relay 7, the lower intermediate armature switch of relay 8 and its normal contact, the upper armature switch of relay 9 and its normal contact, both sides of the calling line, the lower armature switch of 25 relay 9 and its normal contact, the upper immediate armature switch of relay 8 and its normal contact, to the grounded upper winding of relay 7. The relay 7 is energized to establish a circuit traceable from 30 the grounded upper intermediate armature switch of relay 7, the alternate contact of this armature switch, the armature of the sluggishly operating relay 10, the winding of this relay, the winding of motor magnet 35 11, the side switch wiper 12, to the grounded battery 6. The motor magnet 11 thereupon sets the wipers 13, 14, 15, 16, 17 and 18 of an operator selector switch into rotation until the wiper 15 encounters an ungrounded 40 waiting contact whereupon these wipers are arrested. The circuit for the private magnet 19 (which was established upon the initial operation of the motor magnet 11) is opened when the wiper 15 engages an ungrounded 45 contact whereby the side switch wipers 12 and 20 are moved into their second positions, wiper 12 in its second position opening the circuit of the motor magnet 11 causing the wipers 13 to 18 inclusive to 50 remain at rest. When the wiper 12 is in its second position a circuit is established that includes the grounded battery 6, the magnet 21, and the lower grounded armature switch of relay 7 and its then engaged contact, connections 55 from the wipers 16, 17 and 18 being thereupon extended by the attracted armature switches of relay 21. The side switch wiper 20 in its second position grounds the operated wiper 15 so that all 60 contacts in multiple with the contacts en-

gaged by the wiper 15 and belonging to other operator selector switches are grounded so that other operator selector switches cannot engage these contacts that are multiply related with the contacts engaged by the 65 wipers 13 to 18 inclusive, it being understood that the waiting contacts of the different operator selector switches are multiplied as indicated in Fig. 1. The private magnet 19 has been placed in connection 70 with the automatically selected operator whose telephone equipment 22 is in telephonic connection with the waiting contacts engaged by the wipers 13 and 14 that constitute separable terminal connections of the 75 calling line. Both stations 120 and 190 have similar line equipment (in the embodiment of the invention illustrated) and both are adapted similarly to become selectively connected with an idle operator and similar 80 parts of these line equipments are given similar characters of reference, though of course it is to be understood that the invention is not to be limited to mechanism for automatically selecting idle operators. After 85 the calling subscriber has informed the selected operator, which operator, in the embodiment of the invention here shown, may be considered the A operator, will separate the contacts of a key 23 for the purpose of 90 opening the circuit of the line relay 24 of an associate telephone line selector switch, which switch is adapted to select a telephone line that is free for selection and which intervenes between the A and B operators' 95 positions and which telephone line, in the embodiment of the invention here shown, is also adapted to constitute a link connector in an established connection between calling and called stations though such selected telephone line would not be limited to this additional and line joining function. The circuit for the relay 24 that is broken at 23 is traceable from the grounded battery 6, the lower winding of relay 24, the intermediate armature switch of relay 25 and its normal contact, the intermediate armature switch of relay 21 and its then engaged contact, the actuated wiper 17 and its then engaged waiting contact, the 100 contacts of key 23 which are included between contacts of key 26, the actuated wiper 16 and its then engaged waiting contact, the uppermost armature switch of relay 21 and its then engaged contact, the uppermost armature switch of relay 25 and its normal contact to the upper grounded coil of relay 24. When this relay 24 was energized a circuit was established by its lower grounded armature switch through the alternate contact of this switch, the winding of sluggishly operating release control relay 27, and the grounded battery 6. 105 Owing to the sluggishness of the relay 27 the armature switches of this relay are not 110

released when circuit is initially opened at 23 so that when circuit is opened at 23 another circuit is established that may be traced from the grounded armature switch of relay 24, the normal contact of this armature switch, the lower armature switch of sluggishly operating relay 27 and the alternate contact of this switch, the winding of sluggishly operating private control relay 28, the vertical magnet 29, side switch wiper 30 in its first position to the grounded battery 6. The key 23 is diagrammatically shown but it is understood that mechanism is present whereby it is operated at a rate of speed to prevent the relays 27 and 28 from releasing their armatures during the transmission of impulses by the key 23. The circuit of the private magnet 31 is closed during the attraction of the armature switch of the relay 28 and is opened when this armature switch is released upon the reenergization of the relay 24 consequent upon the continued closure of the contacts at 23 when the switch 23 is at rest. When the circuit of the private magnet is thus opened the side switch wipers 30 and 32 are brought to their second positions, the vertical magnet having raised the wipers 33, 34, 35 to the level of waiting contacts including those contacts having the terminals of the desired link connector or telephone line. When the side switch wiper 30 is in its second position the circuit of the vertical magnet 29 is opened and circuit of the rotary magnet 36 is established through the armature switch of the sluggishly operating relay 37 and the winding of this latter relay. The rotary magnet 36 continues in operation until the wiper 34 encounters an ungrounded waiting contact whereupon the private magnet 31, whose circuit was previously reestablished at the armature switch of the rotary magnet 36, is again included in open circuit to open the circuit of the rotary magnet 36, the side switch wipers 30 and 32 now being brought into their third positions, whereby the wipers 33, 34 and 35 are arrested. When the wiper 30 is in its third position a circuit is established which includes the grounded battery 6, side switch wiper 30, the relay 25, and the upper grounded armature switch of relay 27 and its then engaged contact. The armature switches of relay 25 are thereupon attracted, the two upper armature switches thereof continuing the talking sides of the calling line into connection with the talking wipers 33 and 35 in turn connecting the calling line with the selected telephone or link connector that in this instance terminates in a connecting plug 38 that is adapted for insertion within a jack 39 of some telephone line extension such as the telephone line leading to station 190 which in this instance is taken to be the wanted station. A circuit is now present which is traceable

from the upper grounded winding of the differential relay 40, the upper winding of the relay 41, the upper pair of normally engaged contacts of the ringing key 42, the wiper 33 and its engaged waiting contact, 70 the upper armature switch of relay 25 and its alternate contact, the upper armature switch of relay 21 and its then engaged contact, the upper pair of normally engaged contacts of the key 26, the contacts of key 23, the lower pair of normally engaged contacts of key 26, the wiper 17 and its then engaged contact, the intermediate armature switch of relay 21, the intermediate armature switch of relay 25 and its alternate contact, the talking wiper 35 and its then engaged contact, the lower pair of normally connected contacts of key 42, the lower winding of relay 41, the lower winding of differential relay 40, to the grounded battery 6. Relay 40 being differential, is not now energized but relay 41, whose windings are cumulative, is energized to close circuit through the sluggishly operating release relay 43 whose armature switch places ground upon the conductor leading to the actuated wiper 34 in substitution for the ground removed at the upper armature switch of relay 27 when relay 25 is energized, whereby all contacts of other link connector selector switches in multiple with the contact engaged by the wiper 34 are grounded so that no other link connector selector switch will select the previously appropriated link connector, it being understood that the waiting contacts of the different link connector selector switches are multiply related as indicated in Fig. 2, an additional link connector selector switch being illustrated at the lower portion of Fig. 2, similar parts of the link connector selector switches being given similar characters of reference. 95

The selected operator having selected a free telephone line intervening between the position of the selected operator and the position of the B operator, does not seek telephonic connection with the selected B operator in order immediately to inform her of the wants of the calling subscriber but instead causes a speech recording device to record the wants of the calling subscriber which the A or receiving operator speaks into the recording device whereafter the B operator effects or permits the operation of the recording device to reproduce the speech which it has recorded. This recording device is preferably of a well known type including an endless band of magnetizable steel wire or tape 44 (Fig. 3) suitably driven in a uniform direction by motor mechanism diagrammatically indicated at 45. A recording magnet 46 (preferably including duplicated structures) is cooperatively related with the band 44 and is in- 125 130

cluded in a telephonic circuit that extends to the selected A operators' positions and is controlled as hereinafter specified. The speech recorded by means of magnetic fields induced by the element 46 upon the element 44 and which fields are temporarily fixed upon this element 44 is recorded by means of a reproducing magnet 47, desirably including duplicated structure, this reproducing magnet being included in an induced circuit which is controlled and associated as hereinafter specified. The speech recording magnetic fields upon the band 44 are erased by means of an erasing magnet structure 48 in circuit with battery 49 which is stronger than the batteries 50 and 51 included in the recording and reproducing telephone circuits and the polarity of which battery 49 is reversed with respect to the polarities of the batteries 50 and 51 whereby the speech recording magnetic fields may be properly effaced to prepare the portion of the band 44 having the same for the receipt of the new record. I do not limit myself, however, to the form of speech recording and reproducing apparatus illustrated and described. The selected A operator having selected an idle link connector extending to the position of a B operator 30 presses keys 26 and 52 (whose plungers may be replaced by a single operator actuated element) so as to cut the impulse key 23 out of circuit and substantially simultaneously include the operator's telephone outfit 22 in 35 circuit with the conductors leading to the waiting contacts engaged by the wipers 16, and 17, which wipers in turn are connected with the two upper armature switches of relay 21 whose contacts are connected with 40 the armature switches of relay 25 whereby the operator's telephone equipment 22 is telephonically connected with the talking wipers 33, 35 and the talking sides of the selected link connector. When the key 52 is 45 depressed the ground there indicated is connected with the lower talking side of the connected link connector so as to shunt the upper coil of the differential relay 40 whereby this differential relay is permitted 50 to operate. Relay 41 which was previously energized and which remains energized cooperates with the now effectively energized relay 40 to establish a circuit traceable from the grounded battery 6, the upper armature 55 switch of relay 40 and its then engaged contact, the upper armature switch of relay 41 and its then engaged contact, to the grounded relay 53. The right hand armature switch of relay 53 thereupon establishes a 60 circuit for the motor 45 causing the band 44 to travel between the poles of the magnets associated therewith. The left hand armature switch of relay 53 establishes a circuit for the relay 54 so as to close an induced or secondary circuit at the lower

armature switch of relay 54, this induced circuit including the battery 50, the lower armature switch of relay 54, the recording magnet 46 and an induced or secondary coil 55. The upper armature switch of relay 54 completes the closure of an inducing circuit that includes an inducing coil 56, and a condenser 57 in bridge of the talking sides of the selected link connector whereby telephonic current set up by the A operator at 22 will be manifested in the inducing coil 56 and induced from this coil into the secondary circuit including the induced coil 55 and the recording magnet 46. The elements 56 and 55 thus include the recording magnet 46 in telephonic circuit that contains the induced coil 57 of the telephone equipment 22, the inducing coil 58 in the circuit of the transmitter 59 coöperating with the induced coil 57 to bring the transmitter 59 into telephonic relation with the recording magnet 46. While I have shown this way of establishing a telephonic circuit between recording magnet 46 and the transmitter 59 I do not limit myself to this arrangement. 90 The A operator by speaking into the transmitter 59, causes the manifestation of telephonic currents in the recording magnet 46 so as to induce magnetic fields in the band 44 corresponding to the telephonic currents. 95 The record made is in accordance with the requirements and practice of the system and in this instance may be the number of the desired line, and also the number of the calling line. 100 The erasing magnet 48 has its circuit that includes the erasing battery 49 closed at the intermediate armature switch of relay 54 when the circuit of the recording magnet 46 is closed so that the record upon the portion of the band 44 that is to receive a new record is erased preparatory to the reception of such a new record. After the record has been made by the A operator this operator will release the keys 26 and 52 and close the contacts of key 60 to establish a circuit which may be traced from the grounded battery 6, the contacts of the key 60, the actuating wiper 18 and its then engaged contact, the lowermost armature switch of relay 21, the winding of relay 8, the side switch wiper 32 in its third position, the wiper 34, the armature switch of relay 43 and its then engaged contact, to ground. Relay 8 is thereupon energized to establish 110 a locking circuit through this winding that includes the lowermost armature switch of this relay, the battery 6, and the ground at the armature switch of relay 43 through the path previously traced. Relay 8 now closes 120 and maintains the talking sides of the calling line in circuit with the talking sides of the selected link connector. When the relay 8 is energized relay 7 is deenergized whereby the circuit is established which is trace- 130

able from the intermediate grounded armature switch of relay 7 and its normal contact, the release magnet 61 of the actuated operator selector switch, the previously closed off normal switch 62 to the grounded battery 6. The release magnet 61 thereupon effects the restoration of the side switch wipers 12 and 20 to their first positions and brings the wipers 13 to 18 inclusive to normal. The previously employed operator selector switch is thus restored to normal. When the wiper 17 is restored to normal the distributing ground previously established at 52 is removed from the differential relay 40 whose armature switches are restored to normal. The lower armature switch of relay 40 establishes a circuit that may be traced from this switch which is grounded through its normal contact, the armature switch of sluggishly operating relay 63 (which relay was previously energized when the relay 40 became effectively energized) the winding of relay 64, to the grounded battery 6. When the relay 64 is energized it establishes a locking circuit for itself which is traceable from the grounded battery 6 through the winding of the relay 64, the intermediate armature switch of this relay and its then engaged contact, to the grounded intermediate armature switch of relay 65 and its normal contact. When relay 64 is energized a signal lamp 66 is brought into closed circuit to signify to the selected B operator that a record has been made in the speech recording device belonging to her position. When the differential relay 40 is deenergized circuit for the magnet 53 is opened at the upper armature switch of this relay whereby relay 54 is included in open circuit, the circuits of the inducing coil 56 and induced coil 55 being consequently opened, while the circuits of the recording and erasing magnets are also opened. The circuit of the motor 45 is not however broken until the band driving shaft 68 has completed its cycle, this shaft being in suitable gear connection with a disk 69 having a metallic portion that maintains the circuit for the motor 45 during the time the shaft 68 is to be driven and an insulating portion which breaks the circuit when the cycle rotation of the shaft 68 has been completed. It is the duty of the B operator to learn the nature of this record as soon as opportunity will permit, to which end the B operator depresses a listening key 67. The lower contacts of this key serve, when the key is operated, to establish circuit for the relay 70 whereby the inducing circuit including the reproducing magnet 47 is closed at the left hand armature of this relay to bring the inducing coil 71 into inductive relation with the induced coil 72, the induced coil 72 being connected with the operator's head-telephone 73 by the key 67 when depressed whereby the operator hears the reproduced speech and proceeds to establish the direct connection, the tape 44 being moved through another cycle, for the purpose of reproducing the speech, by the motor 45 whose circuit is now closed at the right hand armature switch of relay 70. The operator, pursuant to instructions conveyed by the reproduced recorded speech, inserts the plug 38 into the jack 39 of the desired line and depresses the ringing key 74 to include the ringing generator 75 in the circuit of the called line. If the calling subscriber has, in the meantime, restored his telephone receiver to its switch hook, the B operator also depresses the ringing key 42 to include the ringing current generator 76 in circuit with the calling line. The relay 41 is a calling subscriber's supervisory relay and the relay 77 is a called subscriber's supervisory relay, the calling supervisory signals 78 being controlled by the calling subscribers and the called supervisory signal 79 being controlled by the called subscribers.

A further description of the supervisory signal apparatus is not necessary as it forms no part of my invention except that it may be stated that the locking circuit of magnet 64 is opened at the intermediate armature switch of relay 65 when this armature switch is removed from its normal contact upon the inclusion of the winding of the relay 65 in a local circuit with the grounded battery 6, the heel of the inserted plug 38, the thimble of the jack 39 receiving the same, and the winding of the cutoff relay 80 by a path which is apparent.

Upon the cessation of conversation between the connected subscribers the plug 38 is taken down whereupon the magnet 65 is deenergized and the relay 43 is in turn deenergized whereby ground is removed from the wiper 34 to cause the circuit of relay 25 to be opened. When the relay 25 is deenergized circuit of the release magnet 81 is established whereupon the side switch wipers 30, 32 and the wipers 33, 34 and 35 are restored to normal. The circuit of relay 8 is also opened whereby the equipment of the calling line is restored to normal.

I have hitherto devised a system wherein talking devices have been employed at an exchange for announcing the designations of calling line extensions and this prior invention forms the subject matter of my co-pending application Serial No. 709,427, filed July 15, 1912. In this application I have disclosed a telephone exchange system including telephone lines extending to an exchange, link connectors at the exchange for uniting said lines, talking devices at the exchange having speech reproducing record portions for speaking line designations, and operator controlled means for interchangeably coupling the talking devices with the

link connectors while said link connectors are free to be taken for use and operated in effecting connection between calling and called lines, and the claims in the said co-pending application are broadly and specifically drawn to cover the invention contained in that system.

While I have herein shown and particularly described the preferred embodiment 10 of my invention, I do not wish to be limited to the precise details of construction and circuit arrangement shown as changes may readily be made without departing from the spirit of my invention, nor do I wish to 15 limit myself, in all embodiments of the invention, to telephone exchange systems.

Having thus described my invention I claim as new and desire to secure by Letters Patent the following:—

- 20 1. A telephone exchange system including telephone lines extending to one operator's position; telephone lines extending to a second operator's position; a link connector intervening between the operators' 25 positions for joining calling and called lines; a speech recording and reproducing apparatus, coupled with the link connector, for reproducing recorded speech in the presence of the second operator and provided with a recording magnet operable by 30 telephonic current; a telephone talking connection intervening between the first operator's position and said recording magnet and including a transmitter at the first 35 operator's position; and means governed at the first operator's position for placing said apparatus in condition to receive the record to be reproduced in the presence of the second operator.
- 40 2. A telephone exchange system including telephone lines extending to one operator's position; telephone lines extending to a second operator's position; a link connector intervening between the operators' 45 positions for joining calling and called lines; a speech recording and reproducing apparatus, coupled with the link connector, operable at the first operator's position to record speech; a telephone connection includ- 50 ing a telephone receiver at the second operator's position and a telephone transmitter constituting a reproducing portion of said speech recording and reproducing apparatus; and means governed at the first 55 operator's position for placing said apparatus in condition to receive the record to be reproduced in the presence of the second operator.
- 60 3. A telephone exchange system includ- 65 ing telephone lines extending to one operator's position; telephone lines extending to a second operator's position; a link connector intervening between the operators' positions for joining calling and called lines; a speech recording and reproducing

apparatus, coupled with the link connector, provided with a recording magnet operable by telephonic current; a telephone talking connection intervening between the first operator's position and said recording magnet and including a transmitter at the first operator's position; a telephone connection including a telephone receiver at the second operator's position and a telephone transmitter constituting a reproducing portion of said speech recording and reproducing apparatus; and means governed at the first operator's position for placing said apparatus in condition to receive the record to be reproduced in the presence of the second operator.

4. A telephone exchange system including telephone lines extending to one operator's position; telephone lines extending to a second operator's position; a link connector intervening between the operators' positions for joining calling and called lines; a speech recording and reproducing apparatus, coupled with the link connector, for reproducing recorded speech in the presence of the second operator and provided with a recording magnet operable by telephonic current; a telephone talking connection intervening between the first operator's position and said recording magnet and including a transmitter at the first operator's position, the link connector that intervenes between the operators' positions entering into the formation of said talking connection; and means governed at the first operator's position for placing said apparatus in condition to receive the record to be reproduced in the presence of the second operator.

5. A telephone exchange system including telephone lines extending to one operator's position; telephone lines extending to a second operator's position; a link connector intervening between the operators' positions for joining calling and called lines; a speech recording and reproducing apparatus, coupled with the link connector, provided with a recording magnet operable by telephonic current; a telephone talking connection intervening between the first operator's position and said recording magnet and including a transmitter at the first operator's position, the link connector that intervenes between the operators' positions entering into the formation of said talking connection; a telephone connection including a telephone receiver at the second operator's position and a telephone transmitter constituting a reproducing portion of said speech recording and reproducing apparatus; and means governed at the first operator's position for placing said apparatus in condition to receive the record to be reproduced in the presence of the second operator.

6. A telephone exchange system including telephone lines extending to one operator's position; telephone lines extending to a second operator's position; a link connector intervening between the operators' positions for joining calling and called lines; a speech recording and reproducing apparatus, coupled with the link connector, for reproducing recorded speech in the presence of the second operator and provided with a recording magnet operable by telephonic current; a telephone talking connection intervening between the first operator's position and said recording magnet 70 and including a transmitter at the first operator's position, the telephone line that intervenes between the operators' positions entering into the formation of said talking connection; a signal device at the second operator's position and individual to the link connector intervening between the operators' positions; means for operating this signal device controlled at the first operator's position; and means governed at the first operator's position for placing said apparatus in condition to receive the record to be reproduced in the presence of the second operator.
7. A telephone exchange system including telephone lines extending to one operator's position; telephone lines extending to a second operator's position; a link connector intervening between the operators' positions for joining calling and called lines; a speech recording and reproducing apparatus, coupled with the link connector, provided with a recording magnet operable by telephonic current; a telephone talking connection intervening between the first operator's position and said recording magnet and including a transmitter at the first operator's position, the link connector that intervenes between the operators' positions entering into the formation of said talking connection; a telephone connection including a telephone receiver at the second operator's position and a telephone transmitter constituting a reproducing portion of said speech recording and reproducing apparatus; a signal device at the second operator's position and individual to the telephone line intervening between the operators' positions; means for operating this signal device controlled at the first operator's position; and means governed at the first operator's position for placing said apparatus in condition to receive the record to be reproduced in the presence of the second operator.
8. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position, the telephone line that intervenes between the operators' positions entering into the formation of said talking 130
- apparatus for reproducing recorded speech in the presence of the second operator and provided with a recording magnet operable by telephonic current; a telephone talking connection intervening between the first operator's position and said recording magnet and including a transmitter at the first operator's position, the telephone line that intervenes between the operators' positions entering into the formation of said talking 75 connection; a signal device at the second operator's position and individual to the telephone line intervening between the operators' positions; and means for operating this signal device controlled at the first operator's position; and serving, when operated to effect a signal, to render ineffective the telephone circuit between the recording magnet and the transmitter associated therewith.
9. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position, the telephone line that intervenes between the operators' positions entering into the formation of said talking connection; a telephone 90 connection including a telephone receiver at the second operator's position and a telephone transmitter constituting a reproducing portion of said speech recording and reproducing apparatus; a signal device at the second operator's position and individual to the telephone line intervening between the operators' positions; and means for operating this signal device controlled at the first operator's position and serving, when operated to effect a signal, to render ineffective the telephone circuit between the recording magnet and the transmitter associated therewith.
10. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position, the telephone line that intervenes between the operators' positions entering into the formation of said talking 125

connection; a signal device at the second operator's position; and means for operating this signal device controlled at the first operator's position and serving, when operated to effect a signal, to render ineffective the telephone circuit between the recording magnet and the transmitter associated therewith.

11. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position, the telephone line that intervenes between the operators' positions entering into the formation of said talking connection; a telephone connection including a telephone receiver at the second operator's position and a telephone transmitter constituting a reproducing portion of said speech recording and reproducing apparatus; a signal device at the second operator's position; and means for operating this signal device controlled at the first operator's position and serving, when operated to effect a signal, to render ineffective the telephone circuit between the recording magnet and the transmitter associated therewith.

12. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position; a signal device at the second operator's position and individual to the telephone lines intervening between the operators' positions; and means for operating this signal device controlled at the first operator's position and serving, when operated to effect a signal, to render ineffective the telephone circuit between the recording magnet and the transmitter associated therewith.

13. A telephone exchange system including telephone lines extending to one operator's position; telephone lines extending to a second operator's position; a telephone line intervening between the operators' positions; a speech recording and reproducing apparatus provided with a recording mag-

net operable by telephonic current; a telephone talking connection intervening between the first operator's position and said recording magnet and including a transmitter at the first operator's position; a telephone connection including a telephone receiver at the second operator's position and a telephone transmitter constituting a reproducing portion of said speech recording and reproducing apparatus; a signal device at the second operator's position and individual to the telephone line intervening between the operators' positions; and means for operating this signal device controlled at the first operator's position and serving, when operated to effect a signal, to render ineffective the telephone circuit between the recording magnet and the transmitter associated therewith.

14. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position; a signal device at the second operator's position; and means for operating this signal device controlled at the first operator's position and serving, when operated to effect a signal, to render ineffective the telephone circuit between the recording magnet and the transmitter associated therewith.

15. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position; a telephone connection including a telephone receiver at the second operator's position and a telephone transmitter constituting a reproducing portion of said speech recording and reproducing apparatus; a signal device at the second operator's position; and means for operating this signal device controlled at the first operator's position and serving, when operated to effect a signal, to render ineffective the telephone circuit between the recording magnet and the transmitter associated therewith.

16. A telephone exchange system includ-

ing telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position; and means for erasing the record controlled at the first operator's position.

17. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position; a telephone connection including a telephone receiver at the second operator's position and a telephone transmitter constituting a reproducing portion of said speech recording and reproducing apparatus; and means for erasing the record controlled at the first operator's position.

18. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position, the telephone line that intervenes between the operators' positions entering into the formation of said talking connection; and means for erasing the record controlled at the first operator's position.

19. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's posi-

tion, the telephone line that intervenes between the operators' positions entering into the formation of said talking connection; a telephone connection including a telephone receiver at the second operator's position 70 and a telephone transmitter constituting a reproducing portion of said speech recording and reproducing apparatus; and means for erasing the record controlled at the first operator's position. 75

20. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position, the telephone line that intervenes between the operators' positions entering into the formation of said talking connection; a signal device at the second operator's position and individual to the telephone line intervening between the operators' positions; means for operating this 80 signal device controlled at the first operator's position; and means for erasing the record controlled at the first operator's position. 85

21. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position, the telephone line that intervenes between the operators' positions entering into the formation of said talking connection; a telephone connection including a telephone receiver at 100 the second operator's position and a telephone transmitter constituting a reproducing portion of said speech recording and reproducing apparatus; a signal device at the second operator's position and individual to the telephone line intervening between the operators' position; means for operating this 105 signal device controlled at the first operator's position; and means for erasing the record controlled at the first operator's position. 110

22. A telephone exchange system including telephone lines extending to one operator's position; telephone lines extending to a second operator's position; a telephone line 115

120

125

130

- intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position, the telephone line that intervenes between the operators' positions entering into the formation of said talking connection; a signal device at the second operator's position and individual to the telephone line intervening between the operators' positions; means for operating this signal device controlled at the first operator's position and serving, when operated to effect a signal, to render ineffective the telephone circuit between the recording magnet and the transmitter associated therewith; and means for erasing the record controlled at the first operator's position.
23. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position, the telephone line that intervenes between the operators' positions entering into the formation of said talking connection; a telephone connection including a telephone receiver at the second operator's position and a telephone transmitter constituting a reproducing portion of said speech recording and reproducing apparatus; a signal device at the second operator's position and individual to the telephone line intervening between the operators' positions; means for operating this signal device controlled at the first operator's position and serving, when operated to effect a signal, to render ineffective the telephone circuit between the recording magnet and the transmitter associated therewith; and means for erasing the record controlled at the first operator's position.
24. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said

recording magnet and including a transmitter at the first operator's position, the telephone line that intervenes between the operators' positions entering into the formation of said talking connection; a signal device at the second operator's position; means for operating this signal device controlled at the first operator's position and serving, when operated to effect a signal, to render ineffective the telephone circuit between the recording magnet and the transmitter associated therewith; and means for erasing the record controlled at the first operator's position.

25. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position, the telephone line that intervenes between the operators' positions entering into the formation of said talking connection; a telephone connection including a telephone receiver at the second operator's position and a telephone transmitter constituting a reproducing portion of said speech recording and reproducing apparatus; a signal device at the second operator's position; means for operating this signal device controlled at the first operator's position and serving, when operated to effect a signal, to render ineffective the telephone circuit between the recording magnet and the transmitter associated therewith; and means for erasing the record controlled at the first operator's position.

26. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position; a signal device at the second operator's position and individual to the telephone line intervening between the operators' positions; means for operating this signal device controlled at the first operator's position and serving, when operated to effect a signal, to render ineffective the telephone circuit between the recording magnet and

the transmitter associated therewith; and means for erasing the record controlled at the first operator's position.

27. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position; a telephone connection including a telephone receiver at the second operator's position and a telephone transmitter constituting a reproducing portion of said speech recording and reproducing apparatus; a signal device at the second operator's position; means for operating this signal device controlled at the first operator's position and serving, when operated to effect a signal, to render ineffective the telephone circuit between the recording magnet and the transmitter associated therewith; and means for erasing the record controlled at the first operator's position.

28. A telephone exchange system including telephone lines extending to one operator's position; telephone lines extending to a second operator's position; a telephone line intervening between the operators' positions; a speech recording and reproducing apparatus for reproducing recorded speech in the presence of the second operator and provided with a recording magnet operable by telephonic current; a telephone talking connection intervening between the first operator's position and said recording magnet and including a transmitter at the first operator's position; a signal device at the second operator's position; means for operating this signal device controlled at the first operator's position and serving, when operated to effect a signal, to render ineffective the telephone circuit between the recording magnet and the transmitter associated therewith; and means for erasing the record controlled at the first operator's position.

29. A telephone exchange system including telephone lines extending to one operator's position; telephone lines extending to a second operator's position; a telephone line intervening between the operators' positions; a speech recording and reproducing apparatus provided with a recording magnet operable by telephonic current; a telephone talking connection intervening between the first operator's position and said recording magnet and including a transmitter at the first operator's position; a telephone con-

nnection including a telephone receiver at the second operator's position and a telephone transmitter constituting a reproducing portion of said speech recording and reproducing apparatus; a signal device at the second operator's position; means for operating this signal device controlled at the first operator's position and serving, when operated to effect a signal, to render ineffective the telephone circuit between the recording magnet and the transmitter associated therewith; and means for erasing the record controlled at the first operator's position.

30. A telephone exchange system including telephone lines extending to one operator's position; telephone lines extending to a second operator's position; a link connector extending between the operators' positions for joining calling and called lines; a speech recording and reproducing apparatus, coupled with the link connector, for reproducing recorded speech in the presence of the second operator and operable to receive a record at the first operator's position for recording speech there spoken; and means governed at the first operator's position for placing said apparatus in condition to receive the record to be reproduced in the presence of the second operator.

31. A telephone exchange system including telephone lines extending to one operator's position; telephone lines extending to a second operator's position; a telephone line extending between the operators' positions; a speech recording and reproducing apparatus for reproducing recorded speech in the presence of the second operator and operable to receive a record at the first operator's position for recording speech there spoken; and means for erasing the record controlled at the first operator's position.

32. A telephone exchange system including telephone lines extending to different operators' positions; a speech recording and reproducing apparatus for reproducing recorded speech in the presence of one operator and operable to receive a record at another operator's position for recording speech there spoken; and means for erasing the record controlled at the latter operator's position.

33. A telephone exchange system including telephone lines extending to one operator's position; telephone lines extending to a second operator's position; a link connector intervening between the operators' positions for joining calling and called lines; a speech recording and reproducing apparatus, coupled with the link connector, for reproducing recorded speech in the presence of the second operator and provided with a recording magnet operable by telephonic current; a telephone talking connection intervening between the first operator's position and said recording magnet and including a transmitt-

ter at the first operator's position; means governed at the first operator's position for placing said apparatus in condition to receive the record to be reproduced in the presence of the second operator; and means governed at the second operator's position for placing said apparatus in condition to reproduce the recorded speech in the presence of the operator at the second operator's position.

34. A telephone exchange system including telephone lines extending to one operator's position; telephone lines extending to a second operator's position; a link connector intervening between the operators' positions for joining calling and called lines; a speech recording and reproducing apparatus, coupled with the link connector, operable at the first operator's position to record speech; a telephone connection including a telephone receiver at the second operator's position and a telephone transmitter constituting a reproducing portion of said speech recording and reproducing apparatus; means governed at the first operator's position for placing said apparatus in condition to receive the record to be reproduced in the presence of the second operator; and means governed at the second operator's position for placing said apparatus in condition to reproduce the recorded speech in the presence of the operator at the second operator's position.

35. A telephone exchange system including telephone lines extending to one operator's position; telephone lines extending to a second operator's position; a link connector intervening between the operators' positions for joining calling and called lines; a speech recording and reproducing apparatus, coupled with the link connector, provided with a recording magnet operable by telephonic current; a telephone talking connection intervening between the first operator's position and said recording magnet and including a transmitter at the first operator's position; a telephone connection including a telephone receiver at the second operator's position and a telephone transmitter constituting a reproducing portion of said speech recording and reproducing apparatus; means governed at the first operator's position for placing said apparatus in condition to receive the record to be reproduced in the presence of the second operator; and means governed at the second operator's position for placing said apparatus in condition to reproduce the recorded speech in the presence of the operator at the second operator's position.

36. A telephone exchange system including telephone lines extending to one operator's position; telephone lines extending to a second operator's position; a link connector intervening between the operators' positions

for joining calling and called lines; a speech recording and reproducing apparatus, coupled with the link connector, for reproducing recorded speech in the presence of the second operator and provided with a recording magnet operable by telephonic current; a telephone talking connection intervening between the first operator's position and said recording magnet and including a transmitter at the first operator's position, 70 the link connector that intervenes between the operators' positions entering into the formation of said talking connection; means governed at the first operator's position for placing said apparatus in condition to receive the record to be reproduced in the presence of the second operator; and means governed at the second operator's position for placing said apparatus in condition to reproduce the recorded speech in the presence of the operator at the second operator's position.

37. A telephone exchange system including telephone lines extending to one operator's position; telephone lines extending to a second operator's position; a link connector intervening between the operators' positions for joining calling and called lines; a speech recording and reproducing apparatus coupled with the link connector, provided with recording magnet operable by telephonic current; a telephone talking connection intervening between the first operator's position and said recording magnet and including a transmitter at the first operator's position, the link connector that intervenes between the operators' positions entering into the formation of said talking connection; a telephone connection including a telephone receiver at the second operator's position and a telephone transmitter constituting a reproducing portion of said speech recording and reproducing apparatus; means governed at the first operator's position for placing said apparatus in condition to receive the record to be reproduced in the presence of the second operator; and means governed at the second operator's position for placing said apparatus in condition to reproduce the recorded speech in the presence of the operator at the second operator's position.

38. A telephone exchange system including telephone lines extending to one operator's position; telephone lines extending to a second operator's position; a link connector intervening between the operators' positions for joining calling and called lines; a speech recording and reproducing apparatus, coupled with the link connector, for reproducing recorded speech in the presence of the second operator and provided with a recording magnet operable by telephonic current; a telephone talking connection intervening between the first operator's 120 125 130

position and said recording magnet and including a transmitter at the first operator's position, the link connector that intervenes between the operators' positions entering 5 into the formation of said talking connection; a signal device at the second operator's position and individual to the telephone line intervening between the operators' positions; means for operating this signal device 10 vice controlled at the first operator's position; means governed at the first operator's position for placing said apparatus in condition to receive the record to be reproduced in the presence of the second operator; and 15 means governed at the second operator's position for placing said apparatus in condition to reproduce the recorded speech in the presence of the operator at the second operator's position.

39. A telephone exchange system including telephone lines extending to one operator's position; telephone lines extending to a second operator's position; a link connector intervening between the operator's positions 20 for joining calling and called lines; a speech recording and reproducing apparatus, coupled with the link connector, provided with a recording magnet operable by telephonic current; a telephone talking connection intervening between the first operator's position and said recording magnet and including a transmitter at the first operator's position, the link connector that intervenes between the operator's positions 25 entering into the formation of said talking connection; a telephone connection including a telephone receiver at the second operator's position and a telephone transmitter constituting a reproducing portion 30 of said speech recording and reproducing apparatus; a signal device at the second operator's position and individual to the telephone line intervening between the operators' positions; means for operating this 35 signal device controlled at the first operator's position; means governed at the first operator's position for placing said apparatus in condition to receive the record to be reproduced in the presence of the second operator; and means governed at the second 40 operator; and means governed at the second operator's position for placing said apparatus in condition to reproduce the recorded speech in the presence of the operator at the second operator's position.

40. A telephone exchange system including telephone lines extending to one operator's position; telephone lines extending to a second operator's position; a link con-

nector extending between the operator's positions for joining calling and called lines; 60 a speech recording and reproducing apparatus, coupled with the link connector, for reproducing recorded speech in the presence of the second operator and operable at the first operator's position; means governed at 65 the first operator's position for placing said apparatus in condition to receive the record to be reproduced in the presence of the second operator; and means governed at the second operator's position for placing said 70 apparatus in condition to reproduce the recorded speech in the presence of the operator at the second operator's position.

41. A telephone exchange system including telephone lines extending to one operator's position; telephone lines extending to a second operator's position; a link connector extending between the operators' positions for joining calling and called lines; a speech recording and reproducing apparatus, 75 coupled with the link connector, for reproducing recorded speech in the presence of the second operator and operable at the first operator's position; and means governed at 80 the first operator's position for placing said apparatus in condition to receive the record to be reproduced in the presence of the second operator.

42. A system of communication including 90 a speech recording and reproducing apparatus operable at one operator's position for recording speech there spoken and reproducing the recorded speech in the presence of an operator at another operator's position; and means for erasing the record 95 controlled at the first operator's position.

43. A system of communication including a speech recording and reproducing apparatus operable at one operator's position for recording speech there spoken and reproducing the recorded speech in the presence of an operator at another operator's position; and means for erasing the record 100 controlled at the first operator's position, there being a telephone transmitter at the first 105 operator's position and a recording magnet forming a part of the recording mechanism and which magnet is in telephonic connection with said transmitter.

In witness whereof, I hereunto subscribe my name this third day of August A. D., 1912.

MORTON L. JOHNSON.
